UNITED STATES PATENT OFFICE.

HERBERT R. KEITHLEY, OF NEW YORK, N. Y.

COMBINED RAIL JOINT AND BOND.

SPECIFICATION forming part of Letters Patent No. 601,263, dated March 29, 1898.

Application filed January 3, 1898. Serial No. 665,367. (No model.)

To all whom it may concern:

Be it known that I, HERBERT R. KEITHLEY, a citizen of the United States, residing at New York, in the county of New York and State 5 of New York, have invented a new and useful Improvement in a Combined Rail Joint and Bond, of which the following is a specification.

The object of my present invention is to 10 combine a bonding-plate with the forged rail-joint described and claimed in my application for patent filed October 6, 1897, Serial No. 654,206.

To this end my invention consists of the construction and the combination of parts, as hereinafter described, and more particularly pointed out in the claims at the end of this specification.

In the accompanying drawings, Figure 1 is 20 an end view of a combined rail joint and bond constructed according to my invention. Fig. 2 is a perspective view illustrating the manner in which the parts are positioned on the meeting ends of two rails preparatory to forming a combined rail joint and bond according 25 to my invention, and Fig. 3 is a perspective view of a completed rail joint and bond.

In nearly all railways where electricity is 30 used as a motive power the rails are bonded or electrically connected together to form conductors for the currents.

In view of the fact that electricity is being 35 widely introduced as a motive power, in some instances replacing steam, it has now become the custom to bond or electrically connect track-rails, even in constructing railways which are designed to employ steam as a motive power.

Bonds or electrical connections for track- 40 rails have usually been adjusted or secured in place independently of the fish-plates or angle-plates used to form the rail-joints, and in all constructions with which I am familiar the conductivity of the bonded joint depends 45 in the care which is exercised in cleaning the parts which form the bond before they are secured in position and in the perfectness of contact secured between the metal (ordinarily copper) which forms the bond and the steel 50 rails.

The especial object of my present invention is, therefore, to provide a combined rail joint

and bond which may be secured in place by a single operation, which will not require the exercise of care in cleaning the parts before 55 they are secured together, and which will insure absolutely perfect contact between the bonding-plate and the rails.

The rail-joint described in my application for patent, Serial No. 654,206, before referred 60 to, consists, essentially, of a single metallic piece, the sides of which are forged into permanent contact with the meeting ends of two rails.

In forming this joint the blank is prefer- 65 ably heated to a high temperature, placed on the meeting ends of two rails, and then is forged by a press (preferably a hydraulic press) to encircle the meeting ends of two rails, the press being kept under high pres- 70 sure on the blank—say from one hundred to three hundred tons—until the blank cools. This will force the joining-piece into permanent contact with the meeting ends of two rails, so that the same when in place will tend 75 to bite and grip the rails.

To form a combined rail joint and bond, I propose to interpose a bonding-plate of copper or other metal of high conductivity between the rails and the joining-piece and to 80 utilize the heavy pressure employed in forging the joining-piece onto the meeting ends of the two rails, so as to form an absolutely perfect contact between the bonding-plate 85 and the rails and also between the joining-piece and the bonding-plate.

Referring to the drawings and in detail, A and B designate two meeting rails.

C designates the joining-piece, which is formed or forged from a U-shaped blank D, 90 (shown in Fig. 2,) and E designates the bonding-plate.

In practice I preferably employ copper for the bonding-plate, and the bonding-plate is made of sufficient cross-section or thickness 95 to have its conductivity equal to at least the conductivity of a rail-section.

In assembling and securing a combined rail joint and bond in position according to my invention the bonding-plate is preferably 100 wrapped or bent around the base-sections of the ends of two meeting rails. The blank for forming the joining-piece is then preferably heated to a high temperature and is placed

in position on the joint outside of the bonding-plate. The blank is then forged by a hydraulic or other press or by drop-forging to encircle the ends of the meeting rails. Then 5 when the joint is thus formed the ordinary bolts *e* may be applied through the joining-piece and held in place by nuts in the ordinary manner.

Instead of employing a bonding-plate which 10 is bent around to inclose simply the bases of the ends of the meeting rails it is obvious that the same may inclose more or less of the cross-sections of the rails or may simply consist of a flat section or plate.

15 I do not wish, therefore, to be in any way limited to the relative proportions which I have shown and described; but

What I do claim, and desire to secure by Letters Patent of the United States, is—

20 1. A combined rail joint and bond, comprising a single metallic piece forged around the meeting ends of two rails, and a bonding-

plate interposed between the rails and joining-piece, substantially as described.

2. A combined rail joint and bond comprising 25 a single metallic piece forged around the meeting ends of two rails, and a bonding-plate bent around the bases of the meeting rails and interposed between the rails of joining-pieces, substantially as described.

3. A rail-joint comprising a single metallic piece, the sides of which are hot-forged into permanent contact with the meeting ends of two rails, and a bonding-plate bent around the bases of the meeting rails and interposed 35 between the rails and joining-piece, substantially as described.

In testimony whereof I have hereunto set my hand in the presence of two subscribing witnesses.

HERBERT R. KEITIILEY.
